UNITED STATES PATENT OFFICE

157,667

COMBINED WRIST WATCH AND HOLDING STRAP THEREFOR

Sheldon B. Glass, Chicago, Ill.

Application February 8, 1949, Serial No. 747

Term of patent 14 years

(Cl. D42—8)

To all whom it may concern:

Be it known that I, Sheldon B. Glass, a citizen of the United States, residing at Chicago, county of Cook, and State of Illinois, have invented a new, original, and ornamental Design for a Combined Wrist Watch and Holding Strap Therefor, of which the following is a specification, reference being had to the accompanying drawing, forming a part thereof.

Figure 1 is a top plan view of a combined wrist watch and holding strap therefor showing my new design;

Figure 2 is a side view thereof;

Figure 3 is a bottom plan view thereof;

Figure 4 is a right hand end view thereof; and

Figure 5 is a left hand end view thereof.

I claim:

The ornamental design for a combined wrist watch and holding strap therefor, substantially as shown.

S. B. GLASS.
